CLAIM

The ornamental design for a multiple business card holder, as shown and described.

DESCRIPTION

The claimed multiple business card holder is used for displaying a plurality of sets of business cards within one body. Each set is displayed flat with no obstruction to the information on the front of the card contained within.

FIG. 1 is a front view of a multiple business card holder showing my new design;

FIG. 2 is a side cross sectional view thereof;

FIG. 3 is a left side elevational view thereof;

FIG. 4 is a right side elevational view thereof, and,

FIG. 5 is a top view thereof.
